Attorney, Agent, or Firm—Sherman and Shalloway[57] **CLAIM**

The ornamental design for a composite highway toll booth, as shown and described.

DESCRIPTION

FIG. 1 is a perspective front elevational view of the composite highway toll booth of the present invention; FIG. 2 is a perspective rear elevational view of the composite highway toll booth of FIG. 1;

FIG. 3 is a front elevational view of the composite highway toll booth of FIG. 1;

FIG. 4 is a rear elevational view of the composite highway toll booth of FIG. 1;

FIG. 5 is a top plan view of the composite highway toll booth of FIG. 1;

FIG. 6 is an end elevational view of the composite highway toll booth of the present invention wherein the opposite end is a mirror image;

FIG. 7 is a perspective front elevational view of a portion of the composite highway toll booth of the present invention;

FIG. 8 is a perspective rear elevational view of the composite highway toll booth portion of FIG. 2;

FIG. 9 is a front elevational view of the composite highway toll booth of FIG. 7;

FIG. 10 is a rear elevational view of the composite highway toll booth of FIG. 7;

FIG. 11 is a top plan view of the composite highway toll booth of FIG. 7;

FIG. 12 is an end elevational view of the composite highway toll booth of FIG. 7 wherein the opposite end is a mirror image;

FIG. 13 is a perspective front elevational view of a further portion of the composite highway toll booth of the present invention;

FIG. 14 is a perspective rear elevational view of the composite highway toll booth portion of FIG. 13;

FIG. 15 is a front elevational view of the composite highway toll booth of FIG. 13;

FIG. 16 is a rear elevational view of the composite highway toll booth of FIG. 13;

FIG. 17 is a top plan view of the composite highway toll booth of FIG. 13; and,

FIG. 18 is an end elevational view of the composite highway toll booth of FIG. 13 wherein the opposite end is a mirror image.
